LOCATABLE LOUVER OPERATOR

Alvin Lee Miller, 715 W. Redondo Beach, Gardena, Calif.

Filed Nov. 2, 1959, Ser. No. 850,410

6 Claims. (Cl. 20—62)

This invention relates generally to louver operators of the type used to rotate simultaneously a plurality of parallel vertical (or horizontal) louvers, vanes, or shutters, such as those used in windows for protection against the sun. More particularly, this invention relates to a louver operator in which the operator is locatable at any point along one frame rail by means of a pair of tracks lying in planes which are preferably substantially normal to each other, one track being provided in the rail to support an operator carriage, and one track being provided on an arc arm which is swung through an arc movement to rotate the louvers between open and closed position. In a preferred form of the invention, the operator is a gear box mounted on said carriage in alignment with the pivots of louvers, and adapted to swing said arc arm by means of an operator arm of the same length as louver turning arms connected to said arc arm, coupling the two said arc arms being made by means of an arc arm receiving channel of special cross-section making it readily relocatable.

It has long been known to control the sun and air entering a window by means of vanes or louvers disposed either horizontally or vertically in the window, all being simultaneously rotatable about parallel axes passing through pivots in the window frame, or the like. The louvers are usually wide enough so that they overlap slightly when turned into the plane of the window in a closed position; they may be adjusted between the closed position and a fully opened position in which each louver lies substantially in a plane normal to the plane of the window.

The air conditioning of building has greatly spurred the need for and use of louvers external to the window, since the cost of air conditioning, both as to original installation and power required during operation, is enormously affected by the amount of sunlight impinging on glass windows, because of the greenhouse effect. In modern building with large expanses of window space, the peak air conditioning load for areas just inside unprotected windows far exceeds anything that would be required if the windows were protected from direct sunlight at strategic times of the day and year. The installation of moveable louvers external to large window areas on air conditioned buildings has been somewhat inhibited in the past, however, because of problems connected with operating the louvers from inside the window. Satisfactory crank and gear box devices have been available for transmitting crank rotation to a louver movement operator external to the window, but the locating and re-locating of the operator itself has proven to be an expensive job requiring the service of a skilled craftsman.

In modern office buildings, it is the practice to employ only curtain partitions, the support of each floor being derived only from columns. Since the partitions bear no building load, any or all of them can be torn down and relocated to accommodate to the requirements of the tenants. However, moving of a partition frequently requires relocation of the louver operator and the crank by

2

means of which it is operated from inside the window. Also, each section of louvers should be operated by the occupant of the room inside, rather than by the occupant of some neighboring room or office. It is therefore necessary to provide for independent operation of any section of louvers along a glass external wall, depending upon the location of internal partitioning. Drilling of the wall to accommodate the louver crank cannot be avoided, but drilling and redrilling of the louver frame rails and other parts of the louver, everytime in operator is located or relocated produces holes not readily filled by patching and requires a scaffolding or swing stage, external to the building.

Another objection to previously known louver operators has been the tendency of said operators to develop friction or binding at or near the fully closed or fully opened positions. Many previously known operators could not be practically mounted in a manner which permitted operation geometry of the most rational type, i.e. with linkages or levers or rack and pinion arrangements allowing the louvers to rotate freely in their arc of movement.

Still another problem of previously known louver operators has been that of reducing the clearance between the sill and the end of the moveable louver. This clearance should be at a minimum if the louver is to fully cover the window area. Any substantial gap detracts from the appearance esthetically, and makes inefficient use of the window opening.

An outstanding disadvantage of experimental attempts to solve some of the foregoing problems has been that adjustable or relocatable mounting of the louver operator has resulted in a shaky and unreliable mounting for the operator itself, with consequent binding and decline in operating efficiency after a period of use.

It is a major object of the present invention to provide a louver operator system in which the operator can be firmly and rigidly located and relocated at any point along a frame rail of a louver system without the drilling of any holes in the louver system or rail, or otherwise permanently modifying the system in any detectable manner.

It is a further object of the invention to provide a louver operator with perfect operating geometry, for any of several operating means, in a minimum vertical clearance between the sill and the lower end of the moveable louvers. (It will be understood that reference in these objects and the following description to vertical louvers and the sill is used because this is the most common and practical form of louver installation for modern buildings. However, it will also be understood that the invention is equally applicable to louvers which rotate about horizontal or other non-vertical axes, and all description and claims are to be read as including such systems, rather than as being literally confined to vertical louvers, to which reference is made for purposes of description since they are most common.)

Finally, it is a major object of the invention to provide an operator mounting and coupling to the louvers to be operated by said mounting which cooperate to provide rigid support for the operator and its associated mechanism, in a minimum of clearance between the end of the louver and the adjacent window opening.

It will be seen from the following description that the invention provides a flexibly relocatable louver operator system which is no longer subject to the objections of cost, expensive change, and disfiguring alteration of the louver rail or system. The foregoing and other objects and advantages are achieved by provision of a mounting slot in the louver frame rail, for mounting the operator at any point along the rail's link; and by the further provision of an easily relocatable channel-shaped coupling

means which lies in substantially the same plane as that of the lower end of the louvers and the adjacent surface of the frame rail.

The invention will best be understood by the following description of one preferred specific embodiment, taken in connection with the accompanying drawing, in which:

Figure 1 is a front elevational view of a window (broken away in the center to reduce vertical dimension) showing a system of vertical louvers mounted therein between upper and lower rails, with a louver operator locatable in the lower rail;

Figure 2 is an enlarged perspective view of a mounted operator as seen looking slightly downwardly from just inside the lower louver rail;

Figure 3 is a perspective view of the operator of Figure 2, with the crank removed for better viewing, as seen looking upwardly from beneath, and toward the left end, of the lower louver rail; and

Figure 4 is a perspective view of a portion of the coupling employed in the operator system, shown as it serves the additional function of connecting to arc arm sections.

In Figure 1 a number of parallel vertical louvers 10 rotatable about vertical axes through lower and upper pivot points at 11 and 12 in lower and upper rails 13 and 14, respectively. The louver frame work may or may not be completed with side rails 15 and 16, the entire system of louvers 10 being fitted into a window indicated generally by the numeral 17.

The lower rail 13 is seen to be longitudinally slotted in its inner surface, by means of a slot 20, to which is mounted a louver operator 21 best illustrated in Figures 2 and 3.

Figures 1 and 2 show that the louver rail 13 can be mounted on the window sill 18 by means of angle brackets 22, said being provided with slotted screw and bolt openings, 23 and 24, for adjustable mounting to the sill 18 and the rail 13, respectively.

The embodiment of the drawings reveals one preferred form of the invention in which the rail 13 is formed (as an aluminum extrusion or the like) with a horizontal pivot flange 13a, for the mounting of the vertical louvers 10 in a manner to be described hereinafter, and a vertical operator carriage flange 13b, to which an operator carriage 30 is mounted by means of bolts 31 (see Figure 3) received in the slot 20.

It should be noted that the slot 20, seen in cross-section in Figures 2 and 3, is partially enclosed, at its opening, by inwardly projecting shoulders 25 and 24, which extend along all or most of the slot length (although it will be understood that openings might be provided at spaced intervals for introduction of nuts into the slot 20 instead of introduction at the ends thereof only).

Operator 21 is ordinarily a reduction gear enclosed in a gear housing, and operated by a shaft 28 which is rotated by crank 26 by a person inside the building (or by power means, if desired). Ordinarily, the shaft 28 will extend through the wall from the exterior to the interior of the building, in a manner not illustrated since it is common place and used in connection with window operation and the like.

The louvers 10 are sufficiently wide and spaced close enough together along the rail 13 so that they slightly overlap in closed position to provide complete privacy at the window opening.

As seen in Figure 2, the construction of the particular louvers seen in the embodiment employs a right angle flange sheet metal louver arm 40, which has a pivot mounting 41 at or near the lower end of the louver 10, in the upper surface of the pivot mounting flange 13a of lower rail 13. The louver arm 40 is pivotally connected at its swinging or arc arm end 42 by means of a pivot connection 43 to an arc arm 50 which is disposed parallel to rail 13 and in the same plane as pivot mounting flange 13a. It will be understood that the invention is not lim-

ited to the particular shape of louver arm 40, or the particular location of pivot 41 relative to the plane or planes of louver 10, as long as pivot 41 lies in a suitable louver rotation axis. Also, it will be understood that the arc

5 arm 50 is pivotally connected by a pivot connection means like pivot 43 at spaced intervals along its length to a number of louver arms 40 operating a number of parallel louvers 10, this number being at the choice of the builder up to the very substantial number of louvers 10 corresponding to many feet of window width. For purposes of simplicity and clarity only one louver 10 is shown connected to the arc arm 50, but in actuality a single operator 21 will operate a dozen or more louvers, like louver 10, all connected in parallel to the arc arm 15 50.

The arc arm 50 is a long bar running almost the width of the window 17, or the length of the rail 13, at least that portion thereof which is to be controlled by the single operator 21. It is named an arc arm because all points 20 in it must swing through an arc in the plane of the arm 50 and the pivot flange 13a as the pivots 43 for all the parallel louvers 10 are moved between open and closed positions. Thus, in describing said arc, the rail 50 moves in the direction of the arrow 51 towards the pivot flange 13a as the louver 10 is rotated (counter clockwise as seen in Figure 2) toward a closed position as indicated by the arrow 52.

Arc arm 50 has mounted on it from the underside a coupling 60 in the form of a short section of channel.

30 From Figure 4 it is seen that the coupling 60 has one wall 61 (on the right as illustrated) with an inner wall surface which is normal to the back 62 of channel 60 and to the plane in which the arc arm 50 is disposed and moves. The opposite side wall 63 of the coupling 60 is recessed as indicated at 64 in order to receive and hold arc arm 50 by means of an edge shoulder 51 which projects into the longitudinal recess 64 and mates therewith. Thus, coupling 60 can be slipped onto the arc arm 50 from the underside at any point thereof and fastened in position by means of a pair of lock screws 65, which preferably lock at their inner ends into a lock screw slot 52 along the side wall of the arc arm 50.

The coupling 60 may actually serve to splice two sections of arc arm 50a and 50b, as seen in Figure 4, but this is only incidental to its principal purpose, which is to serve as a coupling means to the operator 21 so that the latter can cause the arc arm 50 to describe its arc movement for opening or closing the louvers 10 as already described. Several means of linkage between the operator 50 21 and the coupling 60 are available, and the invention is not restricted in its generic sense to the particular one illustrated, since many other linkage forms will occur to those familiar with the art of transmitting rotation from the output shaft 27 of the operator 21 to the coupling 60 (and thence to arc arm 50), including the horizontally swinging operator arm 70, which is illustrated, as well as rack and pinion, or any other mechanism of the same function. However, the species of the invention which is illustrated has peculiar advantages in compactness and precision geometry as will now be explained.

65 The construction of the specific embodiment shown is readily adaptable to placement of the vertical axis of operator output shaft 27 in the same vertical plane as that defined by all the vertical axes of the louver pivots 41, said line being indicated in Figure 2 by the numeral 71. The radius A of the louver arm 40 may be made equal to the radius B of the operator arm 70. The resulting geometry of the operating linkage is simple and free of any tendency to bind or resist turning. Moreover, the use of a flat sheet metal arm 70 insures sufficient strength in the plane in which stress occurs, while permitting the operator 21, the coupling 60, the arc arm 50, and the operator arm 70 to occupy a minimum of space in the vertical dimension. Thus reducing to a very

small distance the space between the lower ends of the louvers 10 and the sill 18.

While the operator system shown and described herein is fully capable of achieving the objects and providing the advantages hereinbefore stated, it will be realized that it is capable of considerable modification without departure from the spirit of the invention. Thus, for example, less preferred species of linkage may be used between the operator 21 and the coupling 60, the louver arm 40 may be of very different design and appearance, the rail 13 may be quite different, and the operator carriage may be mounted in a manner different from that shown and may be of a different shape. Moreover, although the embodiment shown achieves strength and stability by having the carriage 30 mounted against a vertical surface of carriage flange 13b and coupled to a substantially horizontal surface on the underside of coupling 60, as indicated by the pivotal connection of operator arm 70 at 74, it will be appreciated that the two planes mentioned may not be at right angles to each other and may be neither horizontal nor vertical, although it will be obvious that stability requires some angle between them.

For the foregoing reasons, I do not mean to be limited to the form shown and described, in the foregoing specification and accompanying drawing.

I claim:

1. In a system of parallel louvers rotatable about parallel axes, a selectively locatable operator which includes: an operator mounting rail disposed along one end of said louvers, a louver turning arm extending from each of said louvers; an arc arm, each of said louver arms being pivotally connected to said arc arm to produce simultaneous turning of said louvers when said arc arm is moved in an arc path in a plane normal to the axes of said louvers; walls defining a longitudinal operator mounting slot in said operator mounting rail on the side thereof adjacent said arc arms, said operator mounting slot being partially covered by an inwardly projecting shoulder along at least one side thereof; an operator means mounted on said operator mounting rail by means received in said operator mounting slot and engaging the inner side of said shoulder thereof; a coupling means removable lockable to said arc arm at a plurality of points therealong; and mechanical means between said operator and said coupling for moving said arc arm in louver turning movement upon operation of said operator.

2. In a system of parallel louvers rotatable about parallel axes, a selectively locatable operator which includes: an operator mounting rail disposed along one end of said louvers, a louver turning arm extending from each of said louvers; an arc arm, each of said louver arms being pivotally connected to said arc arm to produce simultaneous turning of said louvers when said arc arm is moved in an arc path in a plane normal to the axes of said louvers; walls defining a longitudinal operator mounting slot in said operator mounting rail on the side thereof adjacent said arc arms, said operator mounting slot being partially covered by an inwardly projecting shoulder along at least one side thereof; an operator means mounted on said operator mounting rail by means received in said operator mounting slot and engaging the inner side of said shoulder thereof; a coupling in the form of a channel extending longitudinally of said arc arm and receiving said arc arm in said channel between a pair of channel walls, at least one of which at least partially overhangs a portion of said arc arm; locking means for locking said coupling to said arc arm; and mechanical means between said operator and said coupling for moving said arc arm in louver turning movement upon operation of said operator.

3. In a system of parallel louvers rotatable about parallel axes, a selectively locatable operator which includes: an operator mounting rail disposed along one end of said louvers, and having an operator mounting flange extending for substantially the entire length of said

5 rail; a louver turning arm extending from each of said louvers near the end adjacent said operator mounting rail; an arc arm, each of said louver arms being pivotally connected to said arc arm to produce simultaneous turning of said louvers when said arc arm is moved in an arc path in a plane normal to the axes of said louvers; walls defining a longitudinal carriage slot in said operator flange on the side thereof adjacent said arc arms, said carriage slot being partially covered by an inwardly projecting shoulder along at least one side thereof; an operator carriage mountable on said operator flange by means received in said carriage slot and engaging the underside of said shoulder thereof; an operator mounted on said operator carriage; an operator arm extending to said arc arm and adapted to impart arc movement to said arc arm when moved by said operator; and a coupling for pivotally coupling said operator arm to said arc arm, said coupling being in the form of a channel extending longitudinally of said arc arm and receiving said arc arm in said channel between a pair of channel walls, one of which at least partially overhangs a portion of said arc arm.

4. In a system of parallel louvers rotatable in pivots about parallel axes, a selectively locatable operator which 25 includes: an operator mounting rail disposed along one end of said louvers, and having an operator mounting surface extending for substantially the entire length of said rail; a louver turning arm extending from each of said louvers near the end adjacent said operator mounting rail; an arc arm, each of said louver arms being pivotally connected to said arc arm to produce simultaneous turning of said louvers when said arc arm is moved in an arc path in a plane normal to the axes of said louvers; walls defining a longitudinal carriage slot in said operator 30 flange on the side thereof adjacent said arc arms, said carriage slot being partially covered by an inwardly projecting shoulder along each side thereof; an operator carriage mountable on said operator mounting surface by means received in said carriage slot and engaging the undersides of said shoulders thereof; an operator mounted on said operator carriage; an operator arm extending from said operator and rotatable about an axis parallel to the axis of said louvers by said operator; a coupling for pivotally coupling said operator arm to said arc arm, said coupling being in the form of a channel extending 35 longitudinally of said arc arm and receiving said arc arm in said channel between a pair of channel walls, one of which at least partially overhangs a portion of said arc arm; locking means for locking said coupling to said arc arm; and pivot means for connecting said operator arm to said coupling at the face opposite said channel part of said coupling.

5. In a system of parallel louvers moveable in pivots in a pair of rails transversely disposed at opposite ends of said louvers, a selectively locatable operator which 55 includes: an operator mounting rail disposed along one end of said louvers, and having a pivot mounting flange lying in a plane transverse to said louvers and serving as a pivot mount for the pivots at the adjacent end of each 60 of said louvers, and having an operator flange extending from said operator mounting rail opposite said louver ends; a louver turning arm extending from each of said louvers near said pivot in said pivot flange, to a point beyond the edge of said pivot flange; an arc arm disposed parallel to said operator mounting rail and substantially coplanar with said pivot mounting flange, each of said louver arms being pivotally connected to said arc arm to produce simultaneous turning of said louvers when said arc arm is moved in an arc path in a plane 65 normal to the axes of said louvers; walls defining a longitudinal carriage slot in said operator flange on the side thereof adjacent said arc arms, said carriage slot being partially covered by an inwardly projecting shoulder along each side thereof; an operator carriage mountable 70 on said operator flange by means received in said car-

riage slot and engaging the undersides of said shoulders thereof; an operator mounted on said operator carriage; an operator arm extending to said arc arm and adapted to impart arc movement to said arc arm when moved by said operator; a coupling for pivotally coupling said operator arm to said arc arm, said coupling being in the form of a channel extending longitudinally of said arc arm and receiving said arc arm in said channel between a pair of channel walls, one of which at least partially overhangs a portion of said arc arm; locking means for locking said coupling to said arc arm; and pivot means for connecting said operator arm to said coupling at the face opposite said channel part of said coupling.

6. An operator system as described in claim 5 in which said operator arm is caused to rotate about an axis 15

parallel to the axis of said louvers by said operator, and in which said operator is positioned on said operator carriage to place said operator axis in the plane of the axes of said louver pivots, with a distance between said operator axis and said pivot means on said coupling equal to the radius of said lower arm from the louver pivot to said arc arm connection.
